TYPEWRITER ATTACHMENT

Charles Winter, Chicago, Ill., assignor to United Autographic Register Co., Chicago, Ill., a corporation of Illinois

Application April 21, 1934, Serial No. 721,776

6 Claims. (Cl. 197—126)

This invention relates particularly to typewriters adapted to the purpose of filling in forms on continuous-form stationery and more particularly to an attachment for holding carbon strips in interleaved relation with stationery strips so that the carbons may be shifted from an advanced to a succeeding set of forms at the completion of a writing operation.

The primary object of the invention is to provide an extremely light and simple attachment which may be mounted on the platen carriage of a standard typewriting machine when it is desired to do continuous billing work thereon. By employing the present invention, an office having but a limited amount of billing work may do the same on one of the ordinary typewriters.

Various inventions have been made for supporting carbon strips in interleaved relation with the stationery, such as extensions for the typewriter carriage which must be supported on a special track provided on the typewriter frame. Other attachments have been used to grip the carbons after they have been advanced beyond the platen and in some cases carbon packs have been provided with a tail piece having a hook intended to catch on the typewriter mechanism when the carbons are advanced beyond the platen.

In the present invention a light metal frame is supported on the tabulating bar of the machine and is provided with a pair of rear guide arms to prevent the stationery from being pulled out of alignment on the platen by the side movement of the carriage. The carbon strips are attached to a fabric holder which has a rearwardly extending train which is provided with a longitudinal slot. The longitudinal slot is impaled by a capped stud rigidly mounted on the guide frame so that a lost motion connection is provided. When the carbon is advanced beyond the platen the pressure members may be released and the stationery drawn forward by hand while the carbon holder prevents further advancement of the carbons due to engagement of the stud in the slot. As the carbon is backed into writing position the carbon holder slides back on the guide member and the lost motion connection permits this movement without buckling the stationery.

The invention is illustrated in a preferred embodiment in the accompanying drawings in which—

Fig. 1 is a side elevational view of a typewriter with an attachment embodying the present invention; Fig. 2 is a broken longitudinal sectional view on an enlarged scale showing how the flex-

ible carbon holder maintains the carbon strips in interleaved relation with the stationery strips; Fig. 3 is a perspective view of the guide member; Fig. 4 an enlarged plan view of the flexible carbon holder; and Fig. 5 a fragmentary plan view showing the lost motion connection between the guide member and carbon holder.

In the embodiment illustrated A designates a typewriter frame equipped with a platen roll carriage A'; B a guide member adapted to fit on 10 to the tabulating bar or rack bar of the carriage A'; and C a flexible carbon holder adapted to grip the ends of carbon strips interleaved with the stationery.

The typewriter frame A is of the usual construction and is equipped with a laterally shiftable platen roll carriage A' in which is rotatably mounted a platen 6. The usual presser rolls and presser roll release mechanism 7 is provided to press stationery against the platen roll. The 20 carriage is further equipped with a tabulating bar or a rack bar 8 on which is mounted the guide member B.

The guide member B comprises a vertical standard 9 which is bifurcated at its lower end 10 as indicated at 10 so as to slip into a pair of opposed notches on the tabulating bar 8. An L-shaped latch member 11 is riveted to the standard 9 by means of rivets 12 so that the standard is snugly held in position. The central standard 30 9 is flanked by a pair of L-shaped brace members 13, to which are spot-welded laterally extending arms 14 whose ends are upturned to provide journals 15 for a guide roller 16 mounted on trunnions 17. A rearwardly extending curved member 18 is also rigidly connected to the members 9 and 13 and its rear end portion is doubled back as indicated at 19 around the U-shaped member 20 which serves to guide the stationery to the platen roll. A capped stud 21 is rigidly connected to the frame member at the junction of the members 18 and 20.

The carbon holder C preferably is made of a flexible fabric and comprises a plurality of U-shaped cross members 22 which may be stitched 45 or glued at 23 to the rearwardly extending train 24. The train, preferably, is tapered rearwardly and terminates between a pair of stiffening members 25 which may be of cardboard or the like. The train is provided with a longitudinally extending slot 26 which is adapted to be impaled by the capped stud 21 and forms a lost motion connection between the carbon holder and the guide member. Preferably, the edge portions of the train are protected by a binding strip 27 and 55

the front end of the slotted portion is reinforced by a gusset 28 which may be glued or stitched in place.

To load a machine which has been equipped with the attachment the stationery strips 30 are placed on the train of the carbon holder C, which may be entirely removed from the machine, and the strips are threaded between the cross members 22. Carbon strips 31 are then interleaved between the strips and their rear edges folded back over the cross members 22. The assembly may then be placed on the machine so that the stud 21 engages the slot 28 in the train and the advanced edges of the loaded stationery may be turned into writing position by means of the platen roll 6. As the form is filled in the stationery is gradually advanced and finally the carbons 31 may be turned completely beyond the typewriter roll. The presser mechanism is then released by means of the lever 7 and the completed set of forms may be drawn forwardly which will strip the carbons into the next succeeding set of forms due to the fact that the rear end of the slot 6 is engaged by the stud 21. The reinforcing member 25, being stiff, distributes the tension across the train 24 and the holder will not become wrinkled. The completed set of forms may then be detached and the succeeding set of forms set back into typing position by means of the platen roll 6. As the carbons are backed up the train will also move rearwardly and the lost motion connection will prevent the carbon holder from becoming disconnected from the guide member.

The foregoing detailed description is given for clearness of understanding only and no unnecessary limitations should be understood therefrom, but the appended claims should be construed as broadly as permissible, in view of the prior art.

I claim:

1. In combination: a typewriter having a traveling carriage provided with a rotatable platen; a guide member mounted on said carriage to direct continuous-form stationery to said platen, said guide member being equipped with a capped stud; and flexible carbon-holding means adapted to hold carbon strips in interleaved relation with stationery led therethrough, said means being equipped with a fabric train having a longitudi-

nal slot, said slot being impaled by said stud to form a lost motion connection.

2. In combination: a typewriter guide member comprising a standard adapted to engage the tabulating bar of a typewriter, a frame mounted on said standard and equipped at its rear end portion with outwardly and upwardly extending guide-arms, a guide roller journaled in the front end portion of said frame, a capped stud fixedly mounted on the rear portion of said frame; and a fabric carbon holder comprising a rearwardly extending train having a longitudinal slit impaled by said capped stud, and a plurality of cross-members about which carbon strips may be folded and held in interleaved relation with continuous-form stationery.

3. A device as specified in claim 2 in which the cross members of the carbon holder are U-shaped and lie in superposed relation with their end portions stitched to the train.

4. A device as specified in claim 2 in which the rear end portion of the fabric train is provided with a laterally extending stiffening member.

5. In combination: a typewriter having a traveling carriage provided with a rotatable platen; a guide member mounted on said carriage to direct continuous-form stationery to said platen, said guide member being equipped with a capped stud; and a fabric carbon holder comprising a train provided with a longitudinal slot making a lost motion connection with said stud, a plurality of cross bars adapted to hold carbon strips in interleaved relation with continuous-form stationery led from said guide member to the platen, said slot being of sufficient length to permit the cross bars of the carbon holder to be advanced beyond said platen.

6. In combination: a typewriter having a transversely shiftable carriage provided with a rotatable platen; a guide-member connected to said carriage to direct continuous-form stationery to said platen; flexible carbon-holding means adapted to hold carbon strips in interleaved relation with stationery led through said holder; and pin-and-slot connecting means in the rear of said platen forming a lost-motion connection between said carbon-holding means and said guide-member.

CHARLES WINTER.
